STARTING OF INTERNAL COMBUSTION ENGINES

James A. Patterson, Astoria, Long Island, N. Y.

Application May 27, 1939, Serial No. 276,095

10 Claims. (Cl. 123—180)

This invention relates to starting of internal combustion engines and particularly multi-cylinder engines.

Among the objects of the invention is a starting system for such engine combining an arrangement which supplies the cylinder or cylinders in which a piston was stopped in a firing stroke position with an arrangement which assures that the combustible charge supplied to the cylinder or cylinders with a piston somewhere on its firing stroke is ignited so as to explode the charge and impart to the piston a power impulse sufficient to start the engine running.

The foregoing and other objects of the invention will be best understood from the following description of exemplifications thereof, reference being had to the accompanying drawings wherein—

Fig. 1 is a diagrammatic view of a six cylinder engine;

Figs. 2a to 2f are diagrammatic views of the positions of the engine pistons during an operating cycle;

Fig. 3 is a diagrammatic view of a standard type of ignition arrangement used on automotive engines modified to exemplify the principles of the invention;

Fig. 4 is a vertical cross-sectional view through an ignition equipment of the type shown diagrammatically in Fig. 1;

Fig. 5 is a horizontal sectional view along line 5—5 of Fig. 4;

Fig. 6 is a horizontal sectional view along line 6—6 of Fig. 4;

Fig. 7 is a detailed side view of a portion of the ignition equipment;

Fig. 8 is a side elevation of an automotive engine embodying the starting equipment exemplifying one form of the invention;

Fig. 9 is a top view of a modified form of auxiliary distributor member; and

Figs. 10 and 11 illustrate two operating positions of a modified form of contact spring connection to the auxiliary distributor member 51.

Many efforts have been made in the past to eliminate the use of battery-operated electric cranking motors for starting multi-cylinder four-cycle engines, such as those generally used in motor vehicles. Many proposals have been made to start such engines by supplying the cylinder or cylinders in which a piston was stopped while going down on its power or firing stroke with an ignitable, combustible charge, and igniting the charges so that the explosion of the charges shall impart to such piston or pistons a power impulse sufficient to start the engine running with its normal operating cycle.

In the engine starting arrangement of U. S. Reynolds Patent 899,618, the cylinder in which a piston is somewhere on its firing stroke is selec-

tively supplied with an ignitable compressed combustible charge, and a longitudinally slidable valve mechanism is provided for supplying only the cylinders with the piston on its firing stroke with such combustible charge. In Brisbois Patent 1,140,331, another arrangement of this type is described. Christensen Patents 1,185,874, 1,253,466 and 1,253,669 describe engine starting arrangements in which an ignitable compressed combustible charge is supplied to each of the cylinders in their firing order for starting the engine. Brown Patent 2,053,321 shows an arrangement of the type described in the Reynolds Patent 899,618, with a rotary sleeve valve for selectively admitting an ignitable compressed combustible starting charge to the cylinder in which a piston was stopped on its firing stroke.

As far as I know, all prior engine starting arrangements of this type proved unsatisfactory for starting multi-cylinder four-cycle engines such as those generally used in automotive vehicles because of the difficulties in securing automatic selective ignition of the combustible charge delivered to the cylinder in which the piston is somewhere on its power stroke.

In accordance with the invention, the difficulties heretofore encountered with such starting arrangement are eliminated by combining any of the prior art known arrangements for delivering to the cylinders of the engine pistons which are on the downward firing stroke an ignitable combustible charge with a novel starting ignition arrangement which enables selective and reliable ignition of the ignitable combustible starting charges in the cylinders which have a piston somewhere on its downward firing stroke, and particularly, on the part of the firing stroke in which the ignition of the combustible charge will impart to the piston or pistons a power stroke sufficient to start the engine on its normal operating cycle.

The combustible charge for starting the engine may be supplied to the cylinders by any of the known arrangements, for instance, by providing a container with compressed air in which air of a predetermined pressure is automatically maintained by an auxiliary motor-driven compressor, and charging the cylinders having a piston in a firing stroke position with an ignitable compressed combustible charge by using the compressed air discharged into the cylinder for atomizing the proper proportion of gasoline or any other suitable fuel by any of the known carburetor arrangements. Such selective admission of the combustion charge to the cylinders may be effected by longitudinally slidable tubular valves of the type shown in Reynolds Patent 899,618 or by rotary sleeve valves of the type shown in Brown Patent 2,053,321 arranged to cut off the charging ducts from the combustion space of the

cylinders before the charge is ignited, and thereby prevent entrance of carbon into the charging ducts. Alternatively, the combustible charge may be admitted to the cylinders by manually actuated air and fuel injecting pumps which are connected through suitable ducts and rotary or longitudinally slideable valves to the combustion space of the cylinders. Any one of the prior art arrangements for charging the cylinders with the ignitable combustible starting charge may be used as long as the provision is made for admitting a charge to at least one cylinder in which the piston is stopped somewhere in a position on its power stroke before the charge delivered to the cylinder is ignited.

Although the principles of the invention are applicable to most of the available multi-cylinder internal combustion engines, its exemplifications will be described as applied to a typical six cylinder engine shown diagrammatically in Fig. 1 and having six cylinders C1 to C6 with six pistons P1 to P6, being connected as usual to a common crank shaft K.

When such engine is stopped, each of the pistons may occupy any one of the positions which, for instance, piston P1 will occupy while the crank shaft K of the engine completes two revolutions, as illustrated in Fig. 2.

Thus, considering piston P1 as it starts on its firing stroke from the top of its cylinder, as shown in Fig. 2a, it will, during a 60° revolution of the crank shaft, move down on its firing stroke to the position Fig. 2b; then in the next 60° of the crank shaft revolution, it will continue down on the firing stroke to the position Fig. 2c till in the next following 60° of the crank shaft revolution, it will reach the bottom of the firing stroke shown in Fig. 2d. In the further 60° crank shaft revolution, it will move up on its exhaust stroke to the position Fig. 2e, continuing during the next 60° crank shaft revolution on its exhaust stroke to the position Fig. 2f till it reaches in the next 60° crank shaft revolution the top of its exhaust stroke corresponding to the position of cylinder 6 in Fig. 2a. While piston 1 has been thus moving down on its firing stroke and up on its exhaust stroke, its companion piston P6 has been moving down on a suction stroke and up on a compression stroke, and the piston P1, after having reached the top of its exhaust stroke, will in the next full revolution of the crank shaft successively occupy the positions of piston P6 as it moves down on its suction stroke and up on the compression stroke in the way illustrated in Figs. 2a to 2f.

In accordance with the invention, such engine which is stopped with a piston somewhere in its downward firing stroke is started by first charging the cylinders which have the intake and exhaust valves closed with an ignitable combustible charge, and automatically controlling the ignition by means of an auxiliary starting ignition apparatus which is so arranged as to selectively complete an auxiliary ignition circuit to the cylinder or cylinders in which the piston is on its downward firing stroke and selectively produce an ignition discharge in the charged cylinder or cylinders in which the piston is stopped on its downward firing stroke.

The auxiliary starting apparatus is so arranged as to prevent ignition of a combustible charge admitted to a cylinder in which a piston is stopped somewhere on its compression stroke, unless the piston which is stopped somewhere on its downward firing stroke is sufficiently near the

end of its firing stroke that an ignition of a combustible charge admitted to its cylinder would not be sufficient to impart to the engine the power impulse required to start the engine; and to assure that if the piston that is stopped on its firing stroke is near the end of its stroke, an ignitable discharge is produced in the cylinder in which the piston is near the end of its compression stroke, so that the kickback imparted to the 10 crank shaft backs up the piston that was near the end of its firing stroke to an initial position of its firing stroke, for enabling starting of the engine by a follow-up starting operation.

Although the starting ignition arrangement 15 operating according to the principles of the invention may be made in many different forms, it will be explained as applied to the highly developed standard ignition equipments at present generally used on multi-cylinder four-cycle automobile engines, and in particular to a standard ignition equipment used on six-cylinder four-cycle engines as illustrated diagrammatically in Fig. 3 and structurally in Figs. 4 to 8.

The principal parts of the ignition equipment 20 are in the form known commercially as the Delco-Remy type. It comprises an ignition transformer 24 having a primary winding connected through a switch to the positive terminal of a battery 25, the other terminal of which is 25 grounded. The circuit of the primary transformer winding is completed by way of the resistor 26 and the interrupter contacts 28, 29, to the ground, a condenser 27 being connected parallel to contacts 28, 29. A pivotally mounted, 30 grounded, interrupter contact arm 30 carries contact 28 and is biased by a spring 31 to keep the contacts 28, 29, closed so that by actuating the arm 30 to break contacts 28, 29, the battery current through the primary winding of the 35 transformer 24 is broken, and a high voltage is induced in the secondary winding of transformer 24.

The interrupter contacts 28, 29 with the interrupter contact arm 30 form part of a conventional ignition distributing unit, which, as shown 40 in Figs. 4 to 8, comprises a driving shaft 34 revolvably mounted in a casing 35 having a supporting plate on which is mounted the interrupter contact arm 30 with its contacts 28, 29. An interrupter cam 37 keyed to the shaft 34 is engaged by a cam follower 38 extending from the interrupter arm 30 so that as the interrupter cam 37 is rotated, the interrupter contacts 28, 29 are periodically opened.

55 A rotary ignition distributor arm 40, as shown in Fig. 4, of insulating material is likewise keyed to the shaft 34 and is rotated thereby as in conventional ignition distributors so that it makes one complete revolution each time the crank shaft of the engine makes two revolutions corresponding to a full four-stroke operating cycle of all the six cylinders of the engine.

On the distributor arm 40 is mounted a main distributor electrode 41, which is at all times connected through a contact brush spring 42 to the inward end 43 of a high tension terminal member 44 mounted in the center of the insulating cap 45 which is detachably secured to the distributor casing 35. The central high tension terminal 44 of the distributor unit is connected to the high voltage end of the high voltage secondary ignition transformer winding 24, the other end of which is grounded.

On the insulating distributor cap 45 of the distributor casing 35, are also mounted six station-

ary distributor electrode terminals S_1 to S_6 peripherally arranged around the central high voltage terminal 44 , each terminal having an inwardly projecting electrode tip 47 . As in the case of the standard ignition equipment of automotive engines, the six distributor electrode terminals S_1 to S_6 are connected to the spark plugs of the six engine cylinders and the main rotary distributor electrode 41 , is so adjusted relatively to the electrode tips 47 of the distributor terminal electrodes S_1 to S_6 , that when the distributor shaft 34 rotates, its rotating interrupter cam 37 actuates the interrupter arm 30 to open the primary circuit of the ignition transformer 24 six times during each complete revolution of the distributor shaft 34 , at the moments when the main rotary distributor electrode 41 forms successively spark gaps with the electrode tips 47 of the six stationary electrode distributor terminals S_1 to S_6 , for successively completing ignition circuits to the spark gaps of the six cylinders, and apply the high voltage ignition potential induced in the transformer 24 to the spark plugs of the six cylinders in their normal firing order.

The standard ignition equipment of an automotive six-cylinder four-cycle engine so described, is modified in accordance with the principles of the invention by combining with it an auxiliary ignition starting mechanism for selectively igniting the ignitable starting charges supplied to the cylinders in which the intake and exhaust valves are closed and the piston is in a downward stroke position.

As shown diagrammatically in Fig. 3 and structurally in Figs. 4 to 8, the auxiliary starting ignition mechanism comprises an auxiliary rotary distributor member 51 of insulating material revolvably mounted on the cylindrical surface of the main rotary distributor member 40 , and provided with a metallic plate member 52 having a radially projecting auxiliary distributor electrode 53 on which is adjustably mounted the electrode tip 54 . Under normal operating conditions of the engine, the auxiliary distributor member 51 is held biased by a return spring 56 against a stop pin projection 57 of the main distributor 51 , so as to hold the auxiliary distributor electrode 53 aligned with the main distributor electrode 41 without in any way affecting the operation of the main distributor electrode 41 in controlling the ignition of the engine during the normal operation.

The auxiliary distributor member 51 may be rotated through one full revolution against the action of the biasing spring 56 , from its normal full line position in Figs. 3 and 4 until its electrode 53 is brought to the dotted line position $54'$ as in Fig. 5. The circular portion of the metallic plate 52 of the distributor member 40 forms a slip ring, which is engaged by a contact brush spring 58 extending from the main distributor electrode 41 for establishing a positive connection between the auxiliary electrode 53 to the high potential terminal of the ignition transformer 24 . The auxiliary distributor electrode 53 is so adjusted that when the auxiliary distributor member 51 with its electrode 53 are turned one revolution, the auxiliary electrode 53 forms with the electrode tips 47 of the stationary distributor terminals S_1 to S_6 spark gaps through which high voltage ignition current is successively supplied by the ignition transformer 24 to the spark plugs of the six cylinders of the engine.

The auxiliary distributor member 51 is ar-

ranged to be selectively actuated during the starting operation by a mechanism the principles of which will be described in connection with a specific embodiment thereof. It comprises a

driving gear member 60 , and an auxiliary interrupter cam disc 61 , extending from a sleeve 63 slidingly keyed on a shaft 64 which is journaled on brackets 65 , 66 , extending from the supporting plate 36 of the casing 35 . The driving gear 60 is arranged for coupling with the peripheral gear 59 of the auxiliary distributor member 51 , so that by turning the gear 60 , the auxiliary distributor member 51 with its distributor electrode 53 may be rotated from the normal full line position to the dotted line position $54'$ shown in Fig. 4, while the main distributor member 51 is stationary. Under normal conditions, the sleeve 63 with its driving gear 60 and interrupter cam 61 , are biased by a helical return spring 68 against

the outer bracket 66 , the spring 68 serving also to maintain the cam wheel in a normal radial position determined, for instance, by the engagement of a stop pin 69 extending from the shaft 64 , with a stop lug 70 extending from the inner bracket 65 .

The auxiliary interrupter cam wheel 61 has a peripheral cam surface arranged to cooperate with the projecting cam end 71 of the interrupter contact arm 30 , so that when the sleeve 63 is moved against the action of its biasing spring 68 to couple gear 60 with the auxiliary distributor gear 59 , the peripheral portion of the cam wheel 61 comes into engagement with the cam end 71 of the contact arm 30 and actuates it to open, and to retain in the open position its main interrupter contacts 28 , 29 , irrespective of the position of the main interrupter cam 37 . The contact arm 30 is provided with an additional contact 74 which forms with a contact 75 , adjustably mounted on a bracket 76 extending from the supporting plate 36 , a set of auxiliary interrupter contacts for closing and opening the primary circuit, and induce a high voltage ignition current in the secondary winding of the transformer 24 while the main interrupter contacts 28 , 29 remain open.

The auxiliary interrupter contacts 74 , 75 are so adjusted that when the auxiliary interrupter cam 61 is rotated while its cam periphery is engaged by the cam end 71 of the interrupter arm 30 , the teeth of the segmental interrupter cam portions 78 , 79 , will actuate the contact arm 30 to successively reclose and open the auxiliary interrupter contacts 74 , 75 , and induce in the transformer 24 a sequence of high ignition voltages, which the rotating auxiliary distributor electrode 53 applies to the electrodes of the stationary distributor terminals S_1 to S_6 , which the auxiliary electrode 53 passes for applying an ignition voltage only to the spark plugs of cylinders which are correlated to the segmental cam portions 78 , 79 of the auxiliary interrupter cam 61 .

The auxiliary starting ignition mechanism is also shown provided with an operating mechanism comprising a ratchet wheel 80 , mounted on the outwardly protruding end of the shaft 64 , and a ratchet rack 81 held within a rack guide member 83 , and pressed by a biasing spring 84 into engagement with the teeth of the ratchet wheel 80 . The rack guide 83 is shown arranged in the form of an elongated housing structure having slotted side walls through which the shaft 64 projects, so as to guide the rack 81 along the ratchet gear 80 . The inner side wall 81 of the

15

guide 83 serves as a cam arranged to cooperate with a cam knob 89 of the sleeve 63, so that on pulling the guide member 81 against the biasing action of spring 85, the initial movement of the cam wall 87 actuates the cam knob 89 to push the sleeve 63 inwardly to the position in which the driving gear 60 and interrupter arm cam end 71 are coupled to the auxiliary distributor member 51 and auxiliary interrupter cam 61, respectively; and so that upon releasing the guide member 83, the biasing action of spring 85 returns the guide member 83 to the normal position shown in Figs. 3, 8 and 9.

As shown in Figs. 3, 4 and 7, the lower portion of the ratchet rack 81 which moves along the ratchet gear 80 before the cam wall 87 of the guide 83 moves the sleeve 63 with its gear 60 and interrupter cam to their inward coupling position, is without ratchet teeth, so that when the guide 81 is returned to the normal position shown in Figs. 3 and 6, the released uncoupled driving gear 60 and interrupter cam 61, are immediately returned by their biasing spring 68 to their normal radial position shown in Figs. 3 and 4.

The main upper portion of the ratchet rack 81 is provided with ratchet teeth so arranged that in the upward motion of the rack 81 to the normal position shown in Figs. 3, 4 and 7, it imparts to the ratchet gear 80 a rotation so as to rotate the auxiliary distributing electrode 53 from the normal position past all six stationary distributor terminals S1 to S6, while the interrupter contact arm 30 is actuated by the cam segments 78, 79, of the rotating auxiliary interrupter cam 61, to produce a sequence of current interrupting operations which induce in the ignition transformer 24 high ignition voltages only while the auxiliary electrode moves past the selected stationary distributor terminals corresponding to the location of the toothed cam segments 78, 79, of the interrupter cam 61.

Suitable provisions are made in order to assure that when, on starting, the engine starts running on its normal cycles, the rotary motion of the driving shaft 34 of the distributor mechanism does not impart any excessive forces on the elements of the auxiliary starting ignition mechanism. To this end, suitable yieldable coupling connections may be embodied in the driving elements of the auxiliary starting mechanisms. For instance, the driving wheel 60 and driven periphery 59 of the auxiliary distributor member 51, may be provided with frictional coupling surfaces instead of gearing, or frictional driving connections may be embodied at other driving connections of the auxiliary starting mechanism, for instance, between shaft 64 and the driving wheel 61.

In this connection, it may be pointed out that the driving gear 60 should be of the same diameter as the gear 59 of the auxiliary distributor member, so that one revolution of the driving gear 60 turns the auxiliary distributor 51 by one revolution.

The guide member 83 with the associated parts of the control mechanism is held in its operating position adjacent the distributor casing by its sliding engagement with the shaft 64, and is additionally supported by a bracket 91 secured to the distributor casing 35.

The ignition distributor mechanism may be mounted on the engine in the way a standard ignition distributor mechanism is usually mounted, for instance, as shown in Figs. 8 and 9. The operating rack member 83 may be actuated, for

instance, from the dashboard of the car by connecting thereto an actuating member in the form, for instance, of a flexible control rod, such as a Bowden wire 92 of the type generally used in automotive vehicles for actuating from the dashboard operating parts mounted at a distance therefrom.

As shown in Fig. 8, the flexible actuating rod 92 may be guided along the engine in a sleeve 93 clamped by brackets 94 to the exterior of the engine body. The biasing spring 85 is shown clamped to the actuating rod 92 at 95 and abuts against a guide bracket 96 of the rod 92 so as to exert thereon a biasing action which returns the operating rack guide 83 with the rack 81 to the upper normal position shown in Figs. 3 and 4 in which the driving gear 60 and the cam wheel 61 remain in their normal uncoupled positions to which they are biased by their springs 56, 68.

The operating rod 92 is suitably connected to an operating member such as a foot pedal or knob within reach of the driver, for transmitting through the control rod the control action to the control guide member 83 and operate the auxiliary starting ignition arrangement.

The ignition mechanism provided with the auxiliary starting ignition arrangement described above, makes it possible to selectively confine the starting ignition operations to cylinders in which the pistons are stopped somewhere in a position on their downward firing stroke.

Such ignition arrangement may be combined with any of the known arrangements for supplying a starting charge to the cylinders of an engine which has stopped, as described, for instance, in Patents 1,140,331, 1,185,874, 1,253,466, 1,253,669 and 2,053,321. As shown in Fig. 8, the engine has suitably mounted thereon a charging mechanism 101 for supplying a starting charge to the cylinders of an engine which has stopped. The charging mechanism is arranged to be actuated by the actuating rod 92 which is used to actuate the starting ignition mechanism. To this end, a control lever 100 of the charging mechanism may be operatively connected to the actuating rod 92, so that when the actuating rod 92 is pulled outwardly to bring guide 83 of the auxiliary starting ignition mechanism to the downward position, the control lever 100 is actuated to cause the charging mechanism 101 to supply ignitable combustible charges to the cylinders which are used for starting the engine, and to assure that the cylinders which are charged are sealed off ready for ignition, before the starting ignition mechanism is actuated by the motion of the operating rack guide 83 as it is returned to its normal position by the biasing spring 85.

The correlation of the elements of auxiliary interrupter cam 61 and the auxiliary distributor electrode, so as to selectively assure ignition of the ignitable combustible charges supplied to the closed cylinders in which the piston is stopped somewhere on its downward firing stroke or in its upward compression stroke, will now be explained.

As previously explained in connection with Figs. 1, 2 and 3, while a piston, such as piston P1, moves from its position Fig. 2a at which it starts on its firing stroke, to the position Fig. 2c during a 120° crank shaft revolution, the main distributor electrode 41 will move from the firing position opposite distributor electrode S1 leading to the spark of cylinder C1 to the firing position opposite distributor electrode S5 leading to cylinder C5 for igniting the compressed combus-

tible charge in the cylinder C5, which just moved past the dead end position on completing its compression stroke. The operation of each other piston will be similarly correlated to the motion of the main distributor electrode 41 along each arcuate path portion extending between the successive stationary distributor terminals S1 to S6.

In most multi-cylinder internal combustion four-cycle engines, if the piston is on the last part or low power range of its firing stroke, corresponding approximately to about the last third thereof, the explosion of an ignitable combustible charge in its cylinder will in many cases not be able to impart to the piston a sufficient power impulse for causing the engine to start. It is accordingly important to assure that the starting impulse is imparted to the piston while it is in a position on the main part or high power range of its downward firing stroke, corresponding to about the first two-thirds thereof.

The auxiliary starting ignition arrangement of the invention is so designed as to assure that when an engine is stopped with at least one of its pistons on the main high power range of its downward firing stroke, an ignitable combustible charge admitted to the cylinder of such piston is ignited to impart to the piston the power impulse required for starting the engine; and to assure that in the event the engine is stopped with the piston somewhere on the low-power part of the firing stroke, the ignitable combustible charge supplied to the cylinder having a piston which is in the upper part of the compression stroke is ignited, so that the kickback impulse imparted to such piston causes the crank shaft to back up the piston that was in the last part of its firing stroke or the piston ahead of it to a position on the main high-power part of its firing stroke, so that by repeating the starting operation, the piston which is now on the first main high-power part of the firing stroke will receive by the ignition of the combustible charge admitted to its cylinder a power impulse sufficient for starting the engine on its normal operating cycle.

Such selective starting ignition is secured by the ignition starting arrangement exemplifying the invention described above in connection with a six cylinder engine. As explained, the auxiliary distributor electrode 53 is biased so that irrespective of the position in which the engine is stopped, the auxiliary distributor electrode 53 is in a peripheral position determined by the position of the main distributor electrode 41, and the position of the main distributor electrode 41 is definitely correlated to the positions of the several pistons.

Thus, assuming that the engine is stopped while one of its pistons is at the end of the initial fifth of its firing stroke, as indicated diagrammatically in Fig. 3 by the position of the main distributor electrode 41, the auxiliary distributor electrode 53 will automatically be biased to the same angular position while the auxiliary interrupter cam 61 will be biased to its normal stationary position determined by the stop members 69, 70, in which it is out of engagement with the cam follower 71 of the interrupter arm.

If now an ignitable combustible charge is supplied to the cylinders of the pistons which are on the firing and the compression strokes and the auxiliary starting arrangement is actuated by pulling the actuating rack 83 to its downward position against the biasing action of its spring 85, the return movement of the actuating mem-

ber 83 will cause the upwardly moving rack member 81 to impart a rotational movement to the auxiliary distributor electrode 53 and the auxiliary interrupter cam 61. As the auxiliary electrode 53 starts to move in the direction of arrow 110, the initial motion of the auxiliary interrupter cam 61 in the direction of arrow 111 will bring into engagement the initial short toothed cam portion 78 with the cam follower 71 of the interrupter arm 30 so as to generate a short sequence of ignition voltages. The main distributor electrode 41 is shown provided with a tail portion 41t which extends over an arc corresponding to about one-third of the arc between consecutive distributor electrodes S1 to S6, so that the ignition voltage induced by the action of the initial cam teeth 78 of the auxiliary interrupter cam 61 will produce an ignition voltage which will be applied through the tail portion 41t of the main distributor electrode 41 to the spark plug of the cylinder C1 while its piston is still on the main high power part of the firing stroke, and the resulting explosion of the combustible charge will impart to the piston a power impulse sufficient to start the engine.

Assuming now that the engine is stopped at a moment when its main distributor arm 41 is about 30° away from the stationary distributor electrode S1, so that the tail portion 41t of the main distributor electrode does not any more complete an ignition circuit to the spark plug of the cylinder C1, the initial sequence of ignition voltages produced by the rotational movement of the initial interrupter cam tooth portion 78 of the auxiliary interrupter cam 61 will not ignite the combustible charge admitted to cylinder S1. However, in the course of the further rotational movement of the auxiliary distributor electrode 53 in the direction of the arrow 110 and the auxiliary interrupter arm 61 in the direction of the arrow 111, the auxiliary distributor arm 53 will come opposite the electrode of the distributor terminal S1 leading to the spark plug of the cylinder C1 and complete an ignition circuit to its spark plug, while the teeth of the long main interrupter cam portion 79 of the auxiliary interrupter cam 61 actuate the cam follower 71 of the interrupter arm 30 to produce a sequence of ignition voltages, so that an ignition voltage is applied to the spark plug of the cylinder C1 to ignite its combustible charge and impart to its piston P1 which is still in the main high power part of its firing stroke a power impulse sufficient to start the engine.

The starting ignition operation just described will also be effective in igniting the starting charge admitted to cylinder C1 if its piston P1 is stopped on its firing stroke somewhere in a position corresponding to the position of the main distributor electrode 45 somewhere in the initial fifth of its firing stroke, in case the main distributor electrode is made without its tail portion 41t, which is provided in order to positively assure ignition of the starting charge admitted to a cylinder in which the piston is stopped on the initial part of its firing stroke.

The front portion 78 of the toothed interrupter cam portion is made sufficiently far from its end 77, so that if the engine is stopped while the distributor arm occupies a position about 50° or more away from the electrode of the distributor terminal S1 corresponding to the position of the piston P1 near the end of the main part of its firing stroke at which a power impulse produced by the combustible charge ignited in its cylinder

might be insufficient to start the engine, the operation of the auxiliary starting ignition arrangement will bring about an explosion of the combustible charge in the cylinder C5 of the piston P5 which is near the end of its compression stroke, because the front portion 78 of the auxiliary interrupter cam 61 will come into engagement with the cam follower 71 of the interrupter arm 30 at the moment when the rotating auxiliary distributor electrode 53 passes opposite the stationary distributor electrode S5, thus completing an ignition path to the spark plug of cylinder C5 while the interrupter arm 30 is actuated to produce a sequence of ignition voltages. The resulting backfiring impulse imparted to the piston P5 will actuate the cam shaft to back up the piston P1 to the main high power part of its firing stroke, so that by actuating the auxiliary starting arrangement including the auxiliary distributor arm 53 and the auxiliary interrupter cam 61 to inject into the closed cylinders a combustible charge and to repeat the starting ignition operation, the combustible charge in cylinder C1 will be ignited so as to impart to its piston P1 which is now in the main part of its firing stroke a power impulse sufficient to start the engine on its normal operating cycle.

Although in the foregoing the operation of the starting arrangement exemplifying the invention was described on the assumption that piston P1 of the engine was stopped somewhere in its firing stroke, it is obvious that the same operating conditions will govern the starting of the engine if any one of its other pistons is stopped on its firing stroke in a way described in connection with piston P1, since the initial positions occupied by the auxiliary starting electrode 53 and the auxiliary interrupter cam 61 will be the same for each of the pistons of the engine.

To start the engine with the starting arrangement described above, the user has merely to pull the operating rod 92 against the force of its biasing spring 85, thereby actuating the control lever 100 of the auxiliary charging mechanism 101 to supply an ignitable combustible charge to the closed cylinders of those in which the pistons are somewhere on the firing and compression strokes, while pulling the actuating rack 83 to the downward position and to release it, so that the return movement of the operating rack 83 will actuate the auxiliary distributor electrode 53 and the auxiliary interrupter cam 61, to selectively apply ignition voltages to the cylinders in which the piston is on its firing stroke in the way described above.

In accordance with the principles of the invention, the so generated continuous sequence of starting ignition voltages are selectively applied to the cylinders in which the piston is stopped somewhere on the main part of the firing stroke, or in which the piston is stopped in the upper part of the compression stroke in the way described in connection with Fig. 3, by modifying the construction of the auxiliary distributor member 51 in the way shown in Fig. 9. As shown in this figure, the modified auxiliary distributor member 51A is arranged to be rotatably mounted on the main distributor member 40 below the main distributor electrode, and has instead of a circular metallic contact plate member 52 a segmental slip ring plate 114 provided with two segmental contact portions 115, 116, arranged to be engaged by the downwardly projecting contact spring 58 extending from the main distributor electrode, so as to provide a connection between

the main distributor electrode 41 to the slip ring 114 only when the contact spring 58 passes over and engages the segment portions 115, 116, when the auxiliary electrode member 51A is rotated during the starting operation relatively to the main distributor member 40.

As shown in Fig. 9, the auxiliary distributor electrode 53A may be provided on an extension of one of the short slip ring segment 115, and the contact portion 58C of the contact spring 58 is arranged to normally rest on the insulating segment 117 separating the slip ring segments 115, 116, so as to assure that under normal operating conditions, the auxiliary distributor electrode 53A is not effective. The arcuate length of the slip ring segments 115, 116, is proportioned and arranged in a way analogous to the toothed cam sections 78, 79, of the auxiliary interrupter cam 61 so as to selectively complete the ignition circuit to the auxiliary electrode 53A only at the time when the ignition voltage is selectively generated and applied to the spark plugs in the arrangement illustrated diagrammatically in Fig. 3.

The starting ignition arrangement may also be modified so as to assure that the ignition circuit is broken while the auxiliary distributor electrode 53 is returned by its biasing spring 56 from its end position to the normal position against its stop 57 in which it is shown in Fig. 3. To this end, the contact spring 58 through which the auxiliary electrode 53 is connected to the high voltage ignition circuit by way of the main distributor electrode 41, may be modified so as to automatically break the connection to the auxiliary electrode when the auxiliary electrode 53 is returned by the biasing spring 56. In the form shown in Figs. 10 and 11, an auxiliary contact spring 58B extending from the main electrode, has at its free end pivotally mounted a contact roller 120 of insulating material in which is embedded a conducting segment 121, which is conductively connected to the contact spring 58B. A stop pin 122 extending from the roller body 120, limits the revolving movement of the roller 120 to the arc defined by the stop lugs 123, 124, extending from the downward end of the contact spring 58 so that when the auxiliary electrode 53 is rotated against the action of its biasing spring 56 by the driving gear 61, while the main distributor arm 41 is stationary, the roller 120 is held through the engagement of stops 123, 124, with the stop pin 122 in the position shown in Fig. 10, so as to establish a conducting circuit connection from the main distributor electrode 41 to the contact plate 52 of the auxiliary distributor electrode 53, and to cause the return motion of the auxiliary electrode 53 to actuate the roller 120 to revolve until its stop pin 122 comes into engagement with the stop lug 124 in the way shown in Fig. 11, so as to break the circuit connection with the main distributor electrode 41 and the auxiliary distributor electrode 53, during the return motion of the auxiliary distributor electrode 53.

In designing the modified starting ignition arrangements of the type shown in Figs. 9 to 11, provision must be made that the gap distance between the points at which the ignition circuit is selectively opened and closed, is large enough to prevent the ignition voltage from breaking down the gap during the starting as well as the normal operation, while the ignition circuit is selectively held open.

Although the principles of the invention have been explained above in connection with an ex-

emplification thereof as applied to a six-cylinder four-cycle engine, its application to other types of multi-cylinder internal-combustion engines having four or more cylinders will be obvious to those skilled in the art. In particular, the principles of the invention lend themselves for application to internal-combustion engines of the four-cycle type as well as the two-cycle type.

Many other modifications of the invention will suggest themselves to those skilled in the art. It is accordingly desired that the appended claims be given a broad construction commensurate with the scope of the invention within the art.

I claim:

1. The method of starting a multi-cylinder internal-combustion engine having at least four cylinders and igniting means, including main ignition distributor means driven by the engine, which comprises the steps of supplying ignitable combustible starting charges to the closed cylinders of the engine, and selectively applying an ignition voltage to an ignitable charge in a cylinder having a piston on a firing stroke if the piston is on the high power part of the firing stroke, or to selectively apply an ignition voltage to an ignitable charge in a cylinder having a piston on the compression stroke for moving a piston which is on the lower part of the firing stroke back to a position in the high power part of its firing stroke so that in a subsequent starting operation an ignition voltage is selectively applied to an ignitable charge in the cylinder in which the piston was moved back to the high power part of its firing stroke.

2. In a multi-cylinder four-cycle internal-combustion engine having at least four cylinders and igniting means, including main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means movable to successively establish ignition circuits to the cylinders in their firing order, and ignition control means operative during the motion of said auxiliary distributor means to impress ignition voltages on said ignition circuits, said auxiliary distributor means and said ignition control means being correlated to said main ignition distributor means and so arranged and designed as to selectively apply ignition voltages to an ignitable charge in a cylinder having a piston in the high power part of the firing stroke.

3. In a multi-cylinder four-cycle internal-combustion engine having at least four cylinders and igniting means, including main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means normally biased to a position corresponding to the momentary position of said

main distributor means and movable during starting to successively establish ignition circuits to the cylinders in their firing order, and ignition control means operative during the motion of said auxiliary distributor means to impress ignition voltages on said ignition circuits, said auxiliary distributor means and said ignition control means being correlated to said main ignition distributor means and so arranged and designed as to selectively apply ignition voltages to an ignitable charge in a cylinder having a piston in the high power part of the firing stroke.

4. In a multi-cylinder four-cycle internal-combustion engine having at least four cylinders and igniting means, including main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means movable to successively establish ignition circuits to the cylinders in their firing order, and ignition control means operative during the motion of said auxiliary distributor means to impress ignition voltages on said ignition circuits, said auxiliary distributor means and said ignition control means being correlated to said main ignition distributor means and so arranged and designed as to selectively apply ignition voltages to an ignitable charge in a cylinder having a piston in the high power part of the firing stroke, if the piston is on the high power part of the firing stroke, and to selectively apply ignition voltages to an ignitable charge in a cylinder having a piston on the compression stroke for moving back a piston that is on the low power part of its firing stroke so that in a subsequent starting operation an ignition voltage is selectively applied to a charge in a cylinder.

5. In a multi-cylinder four-cycle internal-combustion engine having at least four cylinders and igniting means, including main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means normally biased to a position corresponding to the momentary position of said main distributor means and movable during starting to successively establish ignition circuits to the cylinders in their firing order, and ignition control means operative during the motion of said auxiliary distributor means to impress ignition voltages on said ignition circuits, said auxiliary distributor means and said ignition control means being correlated to said main ignition distributor means and so arranged and designed as to selectively apply ignition voltages to an ignitable charge in a cylinder having a piston in the high power part of the firing stroke if the piston is on the high power part of the firing stroke, and to selectively apply ignition voltages

to an ignitable charge in a cylinder having a piston on the compression stroke for moving back a piston that is on the low power part of its firing stroke so that in a subsequent starting operation an ignition voltage is selectively applied to a charge in a cylinder.

6. The method of starting a multi-cylinder internal-combustion engine having at least four cylinders and igniting means, including main ignition distributor means driven by the engine, which comprises the steps of supplying ignitable combustible starting charges to the closed cylinders of the engine and selectively applying an ignition voltage to an ignitable charge in a cylinder having a piston on a firing stroke if the piston is on the high power part of the firing stroke, or to selectively apply an ignition voltage to an ignitable charge in a cylinder having a piston on the compression stroke for moving a piston which is on the lower part of the firing stroke back to a position in the high power part of its firing stroke so that in a subsequent starting operation an ignition voltage is selectively applied to an ignitable charge in the cylinder in which the piston was moved back to the high power part of its firing stroke.

7. In a multi-cylinder internal-combustion engine having at least four cylinders and igniting means, including main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means movable to successively establish ignition circuits to the cylinders in their firing order, and ignition control means operative during the motion of said auxiliary distributor means to impress ignition voltages on said ignition circuits, said auxiliary distributor means and said ignition control means being correlated to said main ignition distributor means and so arranged and designed as to selectively apply ignition voltages to an ignitable charge in a cylinder having a piston in the high power part of the firing stroke.

8. In a multi-cylinder internal-combustion engine having at least four cylinders and igniting means, including main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means movable to successively establish ignition circuits to the cylinders in their firing order, and ignition control means operative during the motion of said auxiliary distributor means to impress ignition voltages on said ignition circuits, said auxiliary distributor means and said ignition control means being correlated to said main ignition distributor means and so arranged and designed as to selectively apply ignition voltages to an ignitable charge in a cylinder having a piston in the high

power part of the firing stroke, if the piston is on the high power part of the firing stroke, and to selectively apply ignition voltages to an ignitable charge in a cylinder having a piston on the compression stroke for moving back a piston that is on the low power part of its firing stroke so that in a subsequent starting operation an ignition voltage is selectively applied to a charge in a cylinder.

9. In a multi-cylinder internal-combustion engine having at least four cylinders and igniting means, including main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means normally biased to a position corresponding to the momentary position of said main distributor means and movable during starting to successively establish ignition circuits to the cylinders in their firing order, and ignition control means operative during the motion of said auxiliary distributor means to impress ignition voltages on said ignition circuits, said auxiliary distributor means and said ignition control means being correlated to said main ignition distributor means and so arranged and designed as to selectively apply ignition voltages to an ignitable charge in a cylinder having a piston in the high power part of the firing stroke if the piston is on the high power part of the firing stroke, and to selectively apply ignition voltages to an ignitable charge in a cylinder having a piston on the compression stroke for moving back a piston that is on the low power part of its firing stroke so that in a subsequent starting operation an ignition voltage is selectively applied to a charge in a cylinder.

10. In a multi-cylinder internal-combustion engine having at least four cylinders and igniting means, including main ignition control means and main ignition distributor means driven by said engine for cyclically impressing ignition voltages on ignitable combustible charges in said cylinders, so as to cyclically explode said charges and impart a continuous succession of power strokes to the pistons of said cylinders, and means for supplying ignitable combustible starting charges to the closed cylinders during a starting operation, means for starting the engine comprising auxiliary ignition means actuatable during the starting operation comprising an auxiliary ignition distributor means movable to successively establish ignition circuits to the cylinders in their firing order, and auxiliary ignition control means operative during the motion of said auxiliary distributor means to render said main ignition control means inoperative and to impress ignition voltages on said ignition circuits in correlation to the motion of said auxiliary distributor means, said auxiliary distributor means and said ignition control means being correlated to said main ignition distributor means and so arranged and designed as to selectively apply ignition voltages to an ignitable charge in a cylinder having a piston in the high power part of the firing stroke.
